UNITED STATES PATENT OFFICE.

HARRY STECKOL, OF HOUSTON, TEXAS.

SIGN SUSPENSION.

Application filed August 8, 1925. Serial No. 48,982.

To all whom it may concern:

Be it known that I, HARRY STECKOL, a citizen of the United States, residing at Houston, Harris County, Texas, have invented a certain new and useful Improvement in Sign Suspensions, of which the following is a specification.

My invention relates to a means for suspending, or mounting, a plurality of display boards or signs upon a supporting arm. It is particularly designed for use along highways in connecting to the support a base upon which information and highway directions may be printed.

An object is to provide a display device, comprising two or more related display boards or plates secured to the support, by a common clamping device, one above and others below the said support. It is desired that the suspension be one allowing oscillation or swinging of the display boards, the lower of which is heavier than the one above, to maintain the signs in erect position. The invention resides in the particular construction and arrangement of the parts and the means by which they are supported.

Referring to the drawing herewith, Fig. 1 is a front elevation of a device embodying the invention. Fig. 2 is a vertical section on the line 2-2 of Fig. 1.

The display boards are suspended upon a support comprising a post 1 which may be tubular, said post having a laterally extending arm 2 at its upper end. The post 1 is secured within a supporting base and I have shown a post hole or recess 3 in the ground in which the post is fixed by cement or concrete 4.

The display boards comprise a lower board

5, of ornamental shape below the arm and a second smaller board 6 above the arm. These two boards or plates 5 and 6 are secured together and to the supporting arm 2 by a plurality of pairs of bearing plates or brackets 7, of which I have shown three in number.

Said bearing plates 7 are arranged in pairs, as shown in Fig. 2. They have flat upper and lower ends and an intermediate portion curved to fit about the side of the arm 2. They are secured to the display boards by bolts or pins 8, as shown. The engagement with the arm 2 may be a loose one, allowing the signs to swing to more particularly attract the attention of the public.

The arrangement, though simple, is particularly economical and effective. The members 7 secure the plates in alignment and act also to secure them pivotally to the supporting arm. The heavier sign is below the arm so that the signs will be held by gravity in erect positions. The further advantages of this arrangement will be obvious.

What I claim as new and desire to protect by Letters Patent is:

A display device comprising a post, a lateral arm thereon, a sign board below said arm, a smaller sign board above said arm, and opposite clamping plates secured at their ends to said boards and including said arm loosely between them to allow a swinging movement of said boards thereon.

In testimony whereof I hereunto affix my signature this 3rd day of August, A. D. 1925.

HARRY STECKOL.
